FIG.5

FIG.6

FIG. 1 is a front and left side perspective view of the typewriter embodying our new design;

FIG. 2 is a right side elevational view thereof;

FIG. 3 is a rear elevational view thereof;

FIG. 4 is a front and left side perspective view of the typewriter design shown in FIG. 1 wherein the keyboard is inset within the surrounding keyboard frame;

FIG. 5 is a right side elevational view thereof; and FIG. 6 is a rear elevational view thereof.

This is a continuation of applications Serial Nos. D. 65,240 filed May 19, 1961 and D. 65,249 filed May 19, 1961, which are now abandoned.

We claim:

The ornamental design for a typewriter, substantially as shown and described.
